UNITED STATES PATENT OFFICE.

JAN KEISER, OF THE HAGUE, NETHERLANDS.

CROSS-BAR FOR ROLLER-CURTAINS.

1,203,356.

Specification of Letters Patent. Patented Oct. 31, 1916.

Application filed March 30, 1916. Serial No. 87,785.

To all whom it may concern:

Be it known that I, JAN KEISER, of The Hague, Netherlands, have invented certain new and useful Improvements in Cross-
5 Bars for Roller-Curtains; and I do hereby declare the following to be a full, clear, and exact description of the invention, such as will enable others skilled in the art to which it appertains to make and use the same,
10 reference being had to the accompanying drawings, and to letters or figures of reference marked thereon, which form a part of this specification.

The here described invention is relating
15 to a cross bar for keeping roller curtains and the like stretched; this bar is to be connected to the curtain and the fringe in such detachable manner that the fringe has no more to be sewn to the curtain while the
20 loop of the latter required until now becomes superfluous. For this purpose the cross bar is provided at its upper and lower ends with a bore hole and a slot or groove extending from same. These grooves allow
25 the fringe and the curtain of being attached to the cross bar in the manner described in the patent application No. 47,336, 1915.

The invention is shown in a form of execution by the accompanying drawing.

30 The end *b* of the curtain *a* is introduced through the slot into the bore hole *d*, then passed around one side *e* (the right side) of the bar *c*, introduced through the slot at the lower side of the bar into the bore hole
35 *f*, passed around the other (left) side *g* of the bar and finally introduced for the second time into the upper groove. The strip *h* with the fringe *i* is clamped in the lower groove by means of a bar or rod *k* provided
40 with a rib *l* this bar clamping also the curtain. A rod *m* of circular section passed longitudinally through the upper bore hole prevents the curtain from leaving the groove. The arrangement of the curtain at
45 right angles with the cross bar is simplified by providing the bar with a groove *n* into which the curtain end is introduced before being introduced into the bore hole *d* and passed around the bar. Notwithstanding
50 the described way of attaching the fringe is to be preferred, the connection may also be realized in any other manner, for example by means of a loop and a rod of circular

section. Both rods clamp the curtain sufficiently to prevent it from being drawn out. 55 The shape of the grooves may be varied within certain limits.

Claims:

1. In a curtain, a cross bar having diametrically opposite slots and interior openings of greater diameter than the slots and with which said slots communicate, a curtain web wrapped around said bar and having bights entering the interior openings through both of said slots, a second bight 60 in said web entering one of the slots and lying within the bight first formed in said web, and rods passing through said bights and lying within said openings and serving to hold said web against escape. 70

2. In a curtain, a cross bar having diametrically opposite slots and interior openings of greater diameter than the slots and with which said slots communicate, a curtain web wrapped around said bar and having bights entering the interior openings through both of said slots, a second bight 75 in said web entering one of the slots and lying within the bight first formed in said web, a suspended member having a bight 80 entering through the other slot, and rods passing through said bights and lying within said openings and serving to hold said web against escape.

3. In a curtain, a cross bar having diametrically opposite slots and interior openings of greater diameter than the slots and with which said slots communicate, a curtain web wrapped around said bar and having bights entering the interior openings 85 through both of said slots, a second bight in said web entering one of the slots and lying within the bight first formed in said web, and rods passing through said bights and lying within said openings and serving 90 to hold said web against escape, together with a supplemental slot to receive the free end of the curtain web, substantially as described. 95

In testimony whereof I have signed my 100 name to this specification, in the presence of two subscribing witnesses.

JAN KEISER.
